ABSTRACT

A decorative lamp string includes a lamp string and a wool supporting strip. The lamp string is provided with a plurality of lamps, and a wire is arranged between two adjacent lamps. The lamp string is connected to the wool supporting strip. The wool supporting strip includes a supporting portion and a cover portion. The cover portion is arranged around the supporting portion. At least part of the lamp string is embedded in the cover portion. The present disclosure further provides a method for manufacturing a decorative lamp string. By the arrangement of the above structure, the lamp string is connected to the wool supporting strip, so that the product is more stable in structure and is more convenient to shape, making it convenient for a user to make various shapes with the lamp string.

DECORATIVE LAMP STRING AND
METHOD FOR MANUFACTURING SAMECROSS-REFERENCE TO RELATED
APPLICATIONS

This application is a Continuation application of U.S. patent application Ser. No. 18/738,688, filed on Jun. 10, 2024, which is a Continuation-In-Part application of U.S. patent application Ser. No. 17/567,053, filed on Dec. 31, 2021, each of which is entirely incorporated herein by reference.

TECHNICAL FIELD

The present disclosure relates to the technical field of electronic devices, and in particular, to a decorative lamp string and a method for manufacturing the same.

BACKGROUND

With the improvement of the living standard, people have increasingly high requirements for the living environment. In festivals, evening parties, and other scenarios, decorations such as lamp strings, wool supporting strips, sequins, and balloons are usually used to decorate the environment and foil the atmosphere. Due to their diverse shapes and colorful flickering lights, holiday lamp strings have a night lighting decorative effect and is the first choice to add festive atmosphere at festivals. The lamp strings are widely used for decoration in rooms, squares, lawns, trees, and other occasions, and play a good decorative effect.

However, the existing lamp strings usually have bare lamps wound or tied to fixtures, and wires between the lamps are directly exposed. The exposed wires are not aesthetically pleasing themselves and appear obtrusive, affecting the decorative effect.

For this purpose, the present disclosure provides a decorative lamp string and a method for manufacturing the same. A lamp string is combined with a wool supporting strip, which can effectively solve the above problems.

SUMMARY

In order to overcome the shortcomings in the prior art, the present disclosure provides a decorative lamp string with a simple structure and a good sealing effect.

The technical solution adopted by the present disclosure to solve the technical problem is as follows.

A decorative lamp string, includes:

a lamp string, wherein the lamp string is provided with a plurality of lamps, and a wire is arranged between two adjacent lamps; and

a wool supporting strip, wherein the lamp string is connected to the wool supporting strip; the wool supporting strip includes a supporting portion and a cover portion; the cover portion is arranged around the supporting portion; and at least part of the lamp string is embedded in the cover portion.

As an improvement of the present disclosure, the lamp string is spirally wound around the wool supporting strip.

As an improvement of the present disclosure, the decorative lamp string further includes several connectors, wherein the lamp string and the wool supporting strip are arranged side by side; the connectors are connected to the lamp string and the wool supporting strip; and two adjacent connectors are spaced apart from each other.

2

As an improvement of the present disclosure, a thickness of the cover portion is greater than or equal to a diameter of the wire.

As an improvement of the present disclosure, the cover portion includes several lint lines; connecting ends of the lint lines are connected to the supporting portion; and free ends of the lint lines are arranged in a manner of facing away from the supporting portion.

As an improvement of the present disclosure, the wool supporting strip is made of textile fibers.

As an improvement of the present disclosure, the decorative lamp string further includes a connecting head, wherein the connecting head is electrically connected to the lamp string; and the connecting head is configured to connect the lamp string to a power supply.

As an improvement of the present disclosure, the decorative lamp string further includes an adjusting device, wherein the adjusting device is electrically connected to the lamp string; the adjusting device further includes a switching device; and the switching device is configured to switch on or switch off the lamp string.

As an improvement of the present disclosure, the lamp string is a light-emitting diode lamp string.

As an improvement of the present disclosure, a cross-sectional area of the wire is not greater than 0.2 square millimeters.

The present disclosure further provides a method for manufacturing a decorative lamp string. The decorative lamp string includes a lamp string and a wool supporting strip; the lamp string is connected to the wool supporting strip; the lamp string is provided with a plurality of lamps; a wire is arranged between two adjacent lamps; the wool supporting strip includes a supporting portion and a cover portion; the cover portion is arranged around the supporting portion; and at least part of the lamp string is embedded in the cover portion.

As an improvement of the present disclosure, the lamp string is spirally wound around the wool supporting strip.

As an improvement of the present disclosure, the method for manufacturing decorative lamp string further includes: providing several connectors, arranging the lamp string and the wool supporting strip side by side, and using the connectors to be connected to the lamp string and the wool supporting strip, wherein two adjacent connectors are spaced apart from each other.

As an improvement of the present disclosure, a thickness of the cover portion is greater than or equal to a diameter of the wire.

As an improvement of the present disclosure, the cover portion includes several lint lines; connecting ends of the lint lines are connected to the supporting portion; and free ends of the lint lines are arranged in a manner of facing away from the supporting portion.

As an improvement of the present disclosure, the wool supporting strip is made of textile fibers.

As an improvement of the present disclosure, a connecting head is electrically connected to the lamp string; and the connecting head is configured to connect the lamp string to a power supply.

As an improvement of the present disclosure, an adjusting device is electrically connected to the lamp string; the adjusting device further includes a switching device; and the switching device is configured to switch on or switch off the lamp string.

As an improvement of the present disclosure, the lamp string is a light-emitting diode lamp string.

As an improvement of the present disclosure, a cross-sectional area of the wire is not greater than 0.2 square millimeters.

The present disclosure has the beneficial effects: By the arrangement of the above structure, the lamp string is connected to the wool supporting strip, and the supporting portion can effectively support the lamp string, so that the product is more stable in structure and is more convenient to shape, making it convenient for a user to make various shapes with the lamp string, such as a deer model and a spider web. Moreover, the supporting portion can support the lamp string to reduce a pressure on all places on the lamp string, prevent the breakage caused by the pressure on the lamp string, and ensure the safety of use of the product; The arrangement of the cover portion can effectively hide the wires of the lamp string. When the lamp string is connected to the wool supporting strip, part of the cover portion that is in contact with the lamp string deforms, so that the lamp string can be embedded and hidden in the cover portion, which can conveniently hide the wires, prevent the wires from being exposed, and make the appearance of the product beautiful; and furthermore, light generated by the lamps irradiate the cover portion, causing diffuse reflection, which can achieve a better lighting effect.

BRIEF DESCRIPTION OF THE DRAWINGS

In order to explain the technical solutions of the embodiments of the present disclosure more clearly, the following will briefly introduce the accompanying drawings used in the embodiments. The drawings in the following description are only some embodiments of the present disclosure. Those of ordinary skill in the art can obtain other drawings based on these drawings without creative work.

The present disclosure is further described below in detail in combination with the accompanying drawings and embodiments.

FIG. 1 is a schematic diagram of a first embodiment of the present disclosure;

FIG. 2 is an enlarged view of circle A in FIG. 1;

FIG. 3 is a partially schematic structural diagram of a first connecting mode of the present disclosure;

FIG. 4 is a cross-sectional view of a first connecting mode of the present disclosure;

FIG. 5 is a cross-sectional diagram of a wool supporting strip of the present disclosure;

FIG. 6 is a partially schematic structural diagram of a second connecting mode of the present disclosure;

FIG. 7 is a cross-sectional view of a second connecting mode of the present disclosure;

FIG. 8 is a schematic diagram of a second embodiment of the present disclosure;

FIG. 9 is an enlarged view of circle B in FIG. 8;

FIG. 10 is a schematic diagram of a third embodiment of the present disclosure; and

FIG. 11 is an enlarged view of circle C in FIG. 10.

DETAILED DESCRIPTION OF THE EMBODIMENTS

Referring to FIG. 1 to FIG. 11, a decorative lamp string comprises:

a lamp string 10, wherein the lamp string 10 is provided with a wire 12, and a plurality of lamps 11 mounted sequentially along the wire 12; and

a supporting strip 20 comprising a supporting portion 21 and a cover portion 22; wherein the cover portion 22

covers the periphery of the supporting portion 21, the wire 12 and the lamps 11 are supported on the periphery of the supporting portion 21, and at least a part of the wire 12 is hidden inside the cover portion 22.

5 By using the above structure, the lamps 11 are supported by the supporting strip so that the product is more stable to mount and more convenient to shape, which is convenient for a user to make various shapes such as a deer or a spider web shape. In addition, cover portion 22 hides the wires of 10 the lamp string, which makes the appearance of the product neater and simpler; moreover, since cover portion 22 is mainly covered on the periphery of supporting portion 21 for decorative purposes, the color, shape, material, surface texture and pattern of cover portion 22 can be customized to 15 match the theme corresponding to the shape of the decorative lamp string, for example, to match the shape of a deer, the material of A can be simulated deer's fur or simulated deer's skeleton, and the color of cover portion 22 can be the common color of a deer.

20 Referring to FIG. 4, in this embodiment, wire 12 is fixed to the periphery of the supporting portion 21 in at least one of the following ways:

The wire 12 is wrapped around the supporting portion 21, tied to the supporting portion 21, or the like.

25 Referring to FIG. 7, in another embodiment, at least a part of the wire 12 is fixed to the cover portion 22 in the following ways:

The wire 12 is wrapped around the cover portion 22, tied to the cover portion 22, or the like.

30 In detail, the wire 12 is tied to the cover portion 22 by cable tie.

In this embodiment, the lamp string 10 is spirally wound around the supporting strip 20. Spiral winding the lamp string around the supporting strip 20 can achieve fast and stable connection between the lamp string 10 and the supporting strip 20. The connection mode is simple and stable; the product has high stability; and the production efficiency is high.

35 In this embodiment, the decorative lamp string further includes several connectors 60; the lamp string 10 and the supporting strip 20 are arranged side by side; the connectors 60 are connected to the lamp string 10 and the supporting strip 20; and two adjacent connectors 60 are spaced apart from each other. By the arrangement of the above structure,

40 during use, the connectors 60 connect the lamp string 10 to the supporting strip 20 together, and the plurality of connectors 60 are spaced apart from each other to ensure that all parts of the lamp string 10 and all parts of the supporting strip 20 can be stably connected side by side. Moreover,

45 tying the connectors 60 can also apply a force to the lamp string 10, so that at least part of the lamp string 10 is embedded in the cover portion 22, which further improves the lighting effect of the product. Preferably, the connectors 60 are tying ribbons. The tying ribbons are fast and stable in 50 connection, and has low cost.

55 In this embodiment, a thickness of the cover portion 22 is greater than or equal to a diameter of the wire 12. The thickness of the cover portion is greater than or equal to the diameter of the wire. When the lamp string is spirally wound around the wool supporting strip, the wire of the lamp string can be completely hidden in the cover portion to: prevent the wire from being exposed and ensure the decorative effect of the lamp string.

In this embodiment, cover portion 22 is deformable.

60 In this embodiment, cover portion 22 includes several lint lines 221, the lint lines 221 are deformable for the wire 12 hidden inside; connecting ends of the lint lines 221 are

connected to the supporting portion 21; and free ends of the lint lines 221 are arranged in a manner of facing away from the supporting portion 21. By the arrangement of the above structure, the lint lines outwards extend radially from the supporting portion to form the cover portion. There are small gaps between the lint lines. The light of the lamp string irradiates the lint lines and is reflected between the lint lines, making the lighting effect of the lamp string softer and enhancing the decorative effect of the lamp string.

In this embodiment, the supporting strip 20 is made of textile fibers. The wool supporting strip made of the textile fibers are inexpensive and easy to obtain, which greatly reduces the production cost of the product. Preferably, the wool supporting strip is usually made of polyvinyl chloride (PVC), polyethylene (PE), or polypropylene (PP). The PVC, PE, or PP wool supporting strip has high strength, high corrosion resistance, long service life, and low cost.

In this embodiment, the decorative lamp string further includes a connecting head 30, wherein the connecting head 30 is electrically connected to the lamp string 10; and the connecting head 30 is configured to connect the lamp string 10 to a power supply. By the arrangement of the above structure, the connecting head can achieve electrical connection between the lamp string and an external power supply, such as a storage battery and mains supply, ensuring energy supplying of the product, so that the product can continuously emit light, and the battery life of the product is improved.

In this embodiment, the decorative lamp string further includes an adjusting device 40, wherein the adjusting device 40 is electrically connected to the lamp string 10; the adjusting device 40 further includes a switching device 41; and the switching device 41 is configured to switching on or switching off the lamp string 10. The use of the adjusting device can adjust the lighting effect, such as the color, brightness, and flickering effect of the light, so that a user can freely adjust the lighting effect to achieve a more diverse user experience. Moreover, the switching device can conveniently control the switching on or switching off of the lamp string, making it convenient for a user to operate the lamp string. In addition, energy can be saved, and environmental friendliness can be achieved.

In this embodiment, the lamp string 10 is an LED lamp string. By the arrangement of the above structure, LEDs have the characteristics of small volume, long service life, high brightness, and low heat, which can not only ensure the lighting effect, but also achieve the effect of energy conservation, environmental protection, and reduction of energy consumption. Moreover, the LEDs have high flexibility and can be moderately bent, making it convenient for a user to shape the product. The product can be wound into various shapes to further enhance the decorative effect of the product, such as a deer model or a net. Preferably, a copper wire lamp string can be used. The copper wire lamp string has the advantages of low power consumption, high efficiency, long life, rich colors, and high safety, and is convenient to shape.

In this embodiment, a cross-sectional area of the wire 12 is not greater than 0.2 square millimeters. The cross-sectional area of the wire 12 is not greater than 0.2 square millimeters. By the arrangement of the above structure, the cross-sectional area of the wire is not greater than 0.2 square millimeters, so that the wire can be more easily hidden in the cover portion of the wool supporting strip, and the appearance of the product is attractive. On the other hand, a user can select more kinds of wool supporting strips to improve the applicability of the product.

Referring to FIG. 1 to FIG. 11, a method for manufacturing a decorative lamp string, wherein the decorative lamp string includes a lamp string 10 and a supporting strip 20; the lamp string 10 is connected to the supporting strip 20; the lamp string 10 is provided with a plurality of lamps 11; a wire 12 is arranged between two adjacent lamps 11; the supporting strip 20 includes a supporting portion 21 and a cover portion 22; the cover portion 22 is arranged around the supporting portion 21; and at least part of the lamp string 10 is embedded in the cover portion 22. By the arrangement of the above structure, the lamp string is connected to the wool supporting strip, and the supporting portion can effectively support the lamp string, so that the product is more stable in structure and is more convenient to shape, making it convenient for a user to make various shapes with the lamp string, such as a deer shape and a spider web shape. Moreover, the supporting portion can support the lamp string to: reduce a pressure on all places on the lamp string, prevent the breakage caused by the pressure on the lamp string, and ensure the safety of use of the product; The arrangement of the cover portion can effectively hide the wires of the lamp string. When the lamp string is connected to the wool supporting strip, part of the cover portion that is in contact with the lamp string deforms, so that the lamp string can be embedded and hidden in the cover portion, which can conveniently hide the wires, prevent the wires from being exposed, and make the appearance of the product beautiful; and furthermore, light generated by the lamps irradiate the cover portion, causing diffuse reflection, which can achieve a better lighting effect.

In this embodiment, the lamp string 10 is spirally wound around the supporting strip 20. Spiral winding the lamp string around the supporting strip 20 can achieve fast and stable connection between the lamp string 10 and the supporting strip 20. The connection mode is simple and stable; the product has high stability; and the production efficiency is high.

In this embodiment, the decorative lamp string further includes several connectors 60; the lamp string 10 and the supporting strip 20 are arranged side by side; the connectors 60 are used to be connected to the lamp string 10 and the supporting strip 20; and two adjacent connectors 60 are spaced apart from each other. By the arrangement of the above structure, during use, the connectors 60 connect the lamp string 10 to the supporting strip 20 together, and the plurality of connectors 60 are spaced apart from each other to ensure that all parts of the lamp string 10 and all parts of the supporting strip 20 can be stably connected side by side. Moreover, tying the connectors 60 can also apply a force to the lamp string 10, so that at least part of the lamp string 10 is embedded in the cover portion 22, which further improves the lighting effect of the product. Preferably, the connectors 60 are tying ribbons. The tying ribbons are fast and stable in connection, and has low cost.

In this embodiment, a thickness of the cover portion 22 is greater than or equal to a diameter of the wire 12. The thickness of the cover portion is greater than or equal to the diameter of the wire. When the lamp string is spirally wound around the wool supporting strip, the wire of the lamp string can be completely hidden in the cover portion to: prevent the wire from being exposed and ensure the decorative effect of the lamp string.

In this embodiment, the cover portion 22 includes several lint lines 221; connecting ends of the lint lines 221 are connected to the supporting portion 21; and free ends of the lint lines 221 are arranged in a manner of facing away from the supporting portion 21. By the arrangement of the above

structure, the lint lines outwards extend radially from the supporting portion to form the cover portion. There are small gaps between the lint lines. The light of the lamp string irradiates the lint lines and is reflected between the lint lines, making the lighting effect of the lamp string softer and enhancing the decorative effect of the lamp string.

In this embodiment, the supporting strip **20** is made of textile fibers. The wool supporting strip made of the textile fibers are inexpensive and easy to obtain, which greatly reduces the production cost of the product. Preferably, the wool supporting strip is usually made of PVC, PE, or PP. The PVC, PE, or PP wool supporting strip has high strength, high corrosion resistance, long service life, and low cost.

In this embodiment, the method further includes: providing a connecting head **30**, wherein the connecting head **30** is electrically connected to the lamp string **10**; and the connecting head **30** is configured to connect the lamp string **10** to a power supply. By the arrangement of the above structure, the connecting head can achieve electrical connection between the lamp string and an external power supply, such as a storage battery and mains supply, ensuring energy supplying of the product, so that the product can continuously emit light, and the battery life of the product is improved.

In this embodiment, the method further includes: providing an adjusting device **40**, wherein the adjusting device **40** is electrically connected to the lamp string **10**; the adjusting device **40** further includes a switching device **41**; and the switching device **41** is configured to switching on or switching off the lamp string **10**. The use of the adjusting device can adjust the lighting effect, such as the color, brightness, and flickering effect of the light, so that a user can freely adjust the lighting effect to achieve a more diverse user experience. Moreover, the switching device can conveniently control the switching on or switching off of the lamp string, making it convenient for a user to operate the lamp string. In addition, energy can be saved, and environmental friendliness can be achieved.

In this embodiment, the lamp string **10** is an LED lamp string. By the arrangement of the above structure, LEDs have the characteristics of small volume, long service life, high brightness, and low heat, which can not only ensure the lighting effect, but also achieve the effect of energy conservation, environmental protection, and reduction of energy consumption. Moreover, the LEDs have high flexibility and can be moderately bent, making it convenient for a user to shape the product. The product can be wound into various shapes to further enhance the decorative effect of the product, such as a deer shape or a net shape. Preferably, a copper wire lamp string can be used. The copper wire lamp string has the advantages of low power consumption, high efficiency, long life, rich colors, and high safety, and is convenient to shape.

In this embodiment, a cross-sectional area of the wire **12** is not greater than 0.2 square millimeters. The cross-sectional area of the wire **12** is not greater than 0.2 square millimeters. By the arrangement of the above structure, the cross-sectional area of the wire is not greater than 0.2 square millimeters, so that the wire can be more easily hidden in the cover portion of the wool supporting strip, and the appearance of the product is attractive. On the other hand, a user can select more kinds of wool supporting strips to improve the applicability of the product.

This application also provides a method for providing a decorative lamp string, comprising:

providing a wire **12**;

providing a plurality of lamps **11**, which are mounted sequentially along the wire **12**; and providing a supporting strip **20** comprising a supporting portion **21** and a cover portion **22**, wherein the cover portion **22** covers the periphery of the supporting portion **21**, the wire **12** and the lamps **11** are supported on the periphery of the supporting portion **21**, and at least a part of the wire **12** is hidden inside the cover portion **22**.

10 One or more implementation modes are provided above in combination with specific contents, and it is not deemed that the specific implementation of the present disclosure is limited to these specifications. Any technical deductions or replacements approximate or similar to the method and structure of the present disclosure or made under the concept of the present disclosure shall fall within the scope of protection of the present disclosure.

What is claimed is:

1. A decorative lamp string, comprising:

a wire;

a plurality of lamps, which are mounted sequentially along the wire; and

a supporting strip comprising a supporting portion and a cover portion, wherein the cover portion covers a periphery of the supporting portion, the wire and the lamps are supported on the periphery of the supporting portion, and at least a part of the wire is hidden inside the cover portion;

25 wherein the wire is fixed to the periphery of the supporting portion;

wherein the wire is tied to the supporting portion.

2. The decorative lamp string according to claim 1, wherein the wire is fixed to the cover portion.

3. The decorative lamp string according to claim 2, wherein the wire is wrapped around the cover portion.

35 4. The decorative lamp string according to claim 2, wherein the wire is tied to the cover portion.

5. The decorative lamp string according to claim 1, wherein the cover portion is deformable.

40 6. The decorative lamp string according to claim 1, wherein the cover portion comprises several lint lines; connecting ends of the lint lines are connected to the supporting portion; and free ends of the lint lines face away from the supporting portion.

7. The decorative lamp string according to claim 1, wherein the supporting strip is made of textile fibers.

8. A decorative lamp string, comprising:

a wire;

a plurality of lamps, which are mounted sequentially along the wire; and

a supporting strip comprising a supporting portion and a cover portion, wherein the cover portion covers a periphery of the supporting portion, the wire is fixed to the periphery of the supporting portion, the lamps are exposed from the cover portion and at least a part of the wire is hidden inside the cover portion.

9. The decorative lamp string according to claim 8, wherein the wire is fixed to the periphery of the supporting portion.

60 10. The decorative lamp string according to claim 9, wherein the wire is wrapped around the supporting portion.

11. The decorative lamp string according to claim 9, wherein the wire is tied to the supporting portion.

12. The decorative lamp string according to claim 8, wherein the wire is fixed to the cover portion.

13. The decorative lamp string according to claim 12, wherein the wire is wrapped around the cover portion.

14. The decorative lamp string according to claim 12, wherein the wire is tied to the cover portion.

15. The decorative lamp string according to claim 8, wherein the cover portion is deformable.

16. The decorative lamp string according to claim 8, 5 wherein the cover portion comprises several lint lines, the lint lines are deformable for the wire hidden inside.

17. A method for providing a decorative lamp string, comprising:

providing a wire;

providing a plurality of lamps, which are mounted 10 sequentially along the wire; and

providing a supporting strip comprising a supporting portion and a cover portion, wherein the cover portion covers a periphery of the supporting portion, the wire 15 and the lamps are supported on the periphery of the supporting portion, and at least a part of the wire is hidden inside the cover portion.
